UNITED STATES PATENT OFFICE.

WILLIAM G. LIEBIG, OF DETROIT, MICHIGAN.

STAPLE-FORMING MACHINE.

No. 870,114.

Specification of Letters Patent.

Patented Nov. 5, 1907.

Application filed May 29, 1902. Serial No. 318,836.

To all whom it may concern:

Be it known that I, WILLIAM G. LIEBIG, who am a citizen of the United States, residing at Detroit, county of Wayne, State of Michigan, have invented a certain 5 new and useful Improvement in Staple-Forming Machines, and declare the following to be a full, clear, and exact description of the same, such as will enable others skilled in the art to which it pertains to make and use the same, reference being had to the accompanying drawings, which form a part of this specification.

This invention relates to staple forming mechanism, and has for its object an improved machine especially adapted to form staples and furnish them in position 15 to be driven in connection with, and as a part of, brush making machines.

The device of this application consists of the staple forming portion of a brush making machine, such as is illustrated in my co-pending application, Serial Number 302,965. Except for the pedally operated clutch mechanism whereby the driving gear of the entire machine is thrown into and out of operative connection with the source of power, the machine is wholly automatic.

25 In the drawings:—Figure 1, is a perspective of the entire machine, the pedal piece and the lowermost part of the base portion being omitted for the sake of economy of space. Fig. 2, is a front elevation, partly in section, of the working parts of the machine, the 30 facing or cover piece 13 being removed so that the relation and position of the various slides, which it covers and assists in holding in place, may be seen. Fig. 3, is a sectional elevation at right angles to that shown in Fig. 2, along the line x—x in that figure, and looking 35 toward the right as indicated by the arrows. Fig. 4, is a view of the staple former. Fig. 5, is a view of the slide bar whose reciprocation actuates the picker or brush carrier. Fig. 6, is a perspective of the anvil and its actuating device. Fig. 7, is a view from the rear of 40 the lever whose function it is to retract the anvil and feed the wire forward, and of its supporting slide. Fig. 8, is an elevation of the needle and its regulating feed roller, together with the slide bar which carries and actuates it. Fig. 9, is a sectional elevation of a device 45 for regulating the tension of the wire. Fig. 10, is a detail elevation of the wire-cutting block. Fig. 11, is a plan view from beneath of the wire-cutting members. Fig. 12, is a detail elevation of the wire-cutting block with the movable knife piece 70 removed therefrom.

50 A indicates the supporting or base portion of the machine, from which rises an overhanging arm B, upon which most of the working parts of the mechanism are supported. The upper portion of the former is formed to constitute a bearing J for the horizontal shaft S, from 55 which all of the working parts are actuated, and at one end of which is the driving wheel 12 which is actuated

by the belt 12a; this driving wheel is thrown into and out of operative connection with the shaft S by means of the lever C, which is pivoted at 5, to a projecting shoulder of the arm B, and which is actuated by means 60 of the link L, which is operated by a treadle (not shown). The return of the mechanism when not positively actuated by pressure of the foot of the operator on the treadle to a position of non-engagement with the shaft, is brought about by the upward pull of a 65 spring 7, which is attached to a projecting part of the base piece.

Above the middle portion of the machine, two cam members G and H are mounted on the shaft S; each face of each is provided with suitable cam tracks or 70 races, whose contour and relative position, with respect to one another, has been made a matter of careful previous calculation. Into each of these cam races projects an antifriction roller, as 51, which is mounted on a pin at the upper end of vertical slide bar 50, 75 which is contained in a proper race way in the arm portion B, and reaches downwardly to engaging position with the part of mechanism which it is particularly designed to actuate. The extreme right hand one of these slides 40 engages in the cam race u on the 80 right hand face of the wheel G, and is actuated vertically as the wheel rotates by the engagement of its antifriction roller 40a in the cam race. From the lower end of the slide 40 projects a pivoted bracket 41a, which carries a pawl 41; on each downward stroke of 85 the slide, this pawl engages with its lowermost point the teeth of a ratchet wheel 44, which is fixed to one face of the wire-advancing wheel 45, both of which are pivoted to one end of the lever 46. The lever 46 moves about its pivot pin 4a, which extends into the body 90 portion of the arm, and has its horizontal portion (that carrying the wheel 45) kept pressed firmly downwards by the pressure of the spring 4 against the upper end of its vertical portion; the spring 4 is regulated as to its pressure by a nut 47a, whose bolt rests against the fixed 95 lug 47. The periphery of the wheel 45 is serrated so as to frictionally engage the wire 18, which is uncoiled from the spool 19, and passes between its periphery and the smaller serrated wheel 48, on its way to the staple forming mechanism, the pressure of the spring 4 100 making the engagement of the periphery of the wheel a very positive one. The diameter of the wheel is made a matter of very careful previous calculation, proportionate to the size of wire used, in order that each throw of the wheel caused by the engagement of the 105 pawl 41 against the ratchet 44 the exact length of wire desired may be advanced. The greater the size of the wheel 45 the greater is the length of each advancement of wire, since the size in degrees of the arc through which the wheel turns at each stroke is the same. 110 The return of the pawl piece 41 to a position of alignment as near as may be with the slide 40, after each

stroke against the ratchet, is provided for by the spring 39 shown in Figs. 1 and 7; the tension of the wire just previous to its seizure between the wire advancing wheels just mentioned is provided for by means of the hollow post *l* with a cross perforation for the wire 18 and with two plugs *y* and *t* pressed against the interposed wire by a spring *d* whose tension is regulated by screw *a*. I have found it advisable to attach the wire advancing elements to an actuating slide 10 which is independent of, for instance, the needle carrying slide 50, which carries the shearing block 62, since the jolting of this slide 50 due to the impact of the projection 25 on the arm 23 of the bristle carrier against the roller 52 would tend to interfere with the exact 15 timing of the wire's advance by the movement of the serrated feed rollers. After passing through this tension regulating device, and between the wheels 45 and 48, the wire passes on beyond the edge of the shear block 49 and into the track wherein the staple 20 forming slide and its shearing block 68 reciprocate. This staple former is actuated similarly to the slide 40 by engagement of its antifriction roller 61 in the cam race *g* of the wheel *G*; as it descends, it engages the exposed length of wire which has been projected 25 across its path by the rotation of the wheels 45 and 48; shears it off from the rest of the length by engagement of its cutting face against the block 49, and continuing on its way down, presses it over the projecting part 67^a of the anvil 67, which projects from the rear of the machine 30 chine through a suitable slot in the arm *B*, into the path of the shearing block 68 during a portion of each cycle of its movements. The cavity in the block 68 into which the anvil 67 projects upon its forward movement is shown at 74 in Fig. 11. Its rear end is 35 connected by means of a bolt with the slotted end of one arm 65^a of a bell crank lever 65, which is held in place by a screw or bolt 64, which extends vertically therethrough, and through a lug *p* on the rear of the machine. The arm 66 of this bell crank lever has its 40 free end shaped to engage in the oblique slot 42, which is in the rear face of the block 43, and which is fixed to the lower end of the slide 40, whose downward movement causes the arm 66, engaging as it does in the oblique slot 42, to be moved to the left, thus causing the 45 part 67^a of the anvil to be projected into the path of the staple former 60, as hereinabove described. Similarly the upward or retractile movement of this slide 40 causes the arm 66 to move toward the left, thus causing the retractile movement of the anvil 67, after its 50 function (the formation of the staple over the part 67^a) has been accomplished. The positioning of the cam races *u* and *g* on the two faces of the wheel *G* determines the exact timing desired of these two parts.

The wire cutting block 68 may be a single and solid 55 piece of the desired shape or it may take the form illustrated in Figs. 10, 11, and 12. In this case the oblique cutting edge of the block 49 engages across a correspondingly beveled corner of the block in shearing position with respect to the cutting edge 71 of the adjustable shearing knife 70, which engages in a complementary channeled portion 69 of the block, the radii of the knife piece and of the channeled portion being the same. The exact positioning of the knife 70 is regulated by the engagement of a pin through any desired 60 one of the holes 70^a in the knife and into the hole 70^b

in the channeled portion, this positioning being thereafter rendered more positive and rigid with respect to the body of the block by the tightening of the screws 72. The knife may thus be advanced, as its cutting edge wears by moving the securing pin from one hole 70^a to another until it is nearly used up by gradual grinding off; another fresh knife may then be substituted without discarding the cutting block as a whole.

As shown particularly in Fig. 11 the shearing edge of the block 49, and the complementary edge of the 75 shearing block 68 which is carried by staple-forming slide 60 are somewhat oblique to the line of the wire as it advances across the front of the machine, so that as the wire is sheared by their edges, it is not given a straight cut, but is sliced off at an angle so that the 80 points of the staple formed by the ends of the piece of wire cut off are pointed.

Next adjacent to the staple former 60 is the needle-carrying slide 50, similarly actuated by engagement of its antifriction roller 51 in the cam race *k* in the face of 85 the wheel *H*. Its depression is brought about just at the time when the tuft of bristles gathered by the carrier member 29 has been located at its point of deposit, and at the point where the newly formed staple is to be located over and about it. The roller 52 carried on the face of this slide engages the inclined projection 25 on the upper arm 23 of the carrier 29, and then engages forcibly against the projection 26 thereon, both of which jolts cause the bristles to be shaken out of the notch in which they have been assembled and 90 deposited in position to be driven downward, together with the staple. The needle 54, carried by the slide 50 now comes down upon the top of the staple, through the longitudinal slot 68^a in the block 68 and drives it, with the tuft which it incloses, down through the delivery lips *m*, and into the brush back.

On the lower portion of the knife carrying slide 50 is an eccentric wheel 53, part of whose periphery is notched, while the remainder is regularly circular; against its lowermost portion the upper end of the staple driving needle 54 engages. In case the extreme lower portion of the staple driving needle 54 is broken off, as frequently happens, the substitution of a new needle may be avoided by moving the eccentric piece 53 around, so that a higher, if not the highest, portion 105 of the periphery (that farthest from the pivot 53^a which holds it in place) engages against the end, thus forcing it down so much farther on the slide 50.

Within the cam race *k* on the left hand or outer face of the wheel *H* (viewed from the front of the machine) 115 engages the antifriction roller 57^a, which is carried by slide 57. Its vertical reciprocation, in response to the following of the cam track with the antifriction roller 57^a actuates and causes the oscillation of the pivoted carrier 29 about the fixed pin *n*, because of the engagement 120 of a projecting stud in the rear face of the carrier 29 in the grooved cross head 56 at the lower end of the slide or carrier actuator 57. The reciprocation of the peripheral edge of the carrier 29 against the accumulated store of bristles contained by the feed box *F*, and which are constantly fed forward against the periphery of the carrier by the pressure of the follower 36 against the contained mass of bristles (because of the tension of the weighted cord 36^a against its outer end), need not be further described here, as the brush making feature of 130

the machine forms the particular subject matter of my co-pending application hereinabove referred to.

5 The brush backs are supported on the table 14, which is immediately below the depending portion *m* of the staple forming mechanism. Its height and proximity thereto is regulated by the supporting screw 15, and its angularity, with respect to the tuft inserting mechanism, whether perpendicular or otherwise, is determined by the arm 16, which is pivoted to its lower face 10 and is regulated as to its height by the thumb screw 16^a.

What I claim is:

1. In a staple forming mechanism, the combination of wire gripping and advancing means, means for cutting the wire into lengths of the desired size, comprising a fixed block having an exposed shearing face and a vertically reciprocating shearing block adapted to engage therewith and to subsequently participate in the formation of the staple, an anvil controlled as to its movements by said wire advancing means and adapted to be projected thereby into the path of the reciprocating block during a portion of each cycle of operations, and means engaging through said reciprocating block and deriving its actuation independently of the other elements, adapted to be actuated against the head of the newly formed staple and to descend a specific distance with said block, and thereafter, when said block has ceased its descent, to drive the staple by further downward pressure thereupon, substantially as described.
2. In the staple forming mechanism of a brush making machine, in combination with means for feeding toward a specific length of wire at each cycle of operations, a fixed block beyond whose shearing edge the length of wire is projected, a reciprocating block adapted to sever said length of wire by shearing engagement with respect to said

fixed block, an anvil member projected by the movement of 35 said wire-advancing means into the path of travel of said reciprocating block below the point of severing of the wire, adapted to cooperate with said reciprocating block in bending the wire to staple form, and a driving needle engaging through said reciprocating block, though deriving its actuation independently thereof, said needle moving with said reciprocating block during a portion of each cycle of operations, and thereafter by continued downward movement forcing the staple from the reciprocating block and into a brush back, substantially as described.

3. A staple forming mechanism, having in combination with an anvil member, means for feeding forward a predetermined length of wire, said means actuating by its movement said anvil, a portion of which is connected therewith, wire cutting means a part of which is adapted to 50 participate in the bending of the staple after the desired length of wire has been severed, and a driving needle adapted to engage the staple when formed and to drive the same free from the cutting and forming means, substantially as described.

4. A holder for the driving needle of a staple forming machine, comprising a slide adapted to be reciprocated within a vertical path of travel, said slide being provided with a groove along a portion of its length wherein said needle engages, and an eccentrically pivoted wheel across the upper end of the needle, a portion of the periphery of said wheel being smooth and a portion being serrated, and being adapted to regulate the degree of projection of the needle from the slide, because of said eccentricity of pivoting, substantially as described.

In testimony whereof, I sign this specification in the presence of two witnesses.

WILLIAM G. LIEBIG.
